APPARATUS FOR FORMING METAL BODIES

John A. Johnson, Woodhaven, N. Y.

Application May 2, 1936, Serial No. 77,589

20 Claims. (Cl. 113—11)

This invention relates to apparatus for forming sheet metal bodies of tubular form, particularly used in the manufacture of spools having annular heads of sheet material secured to the opposite ends of the bodies, and it is the principal object of the invention to provide an apparatus in which a plurality of blanks are simultaneously and progressively operated on automatically.

It is an object of the invention to provide an apparatus which is readily adjustable to form sheet metal bodies of various lengths.

It is another object of the invention to feed the body blanks to the apparatus by a novel arrangement of suction means.

It is a further object of the invention to provide a novel arrangement of parts to notch the corners of the blank without injuring the blank.

Another object of the invention is to provide novel means to intermittently advance the blanks through the apparatus without the use of an excessive number of parts.

A further object of the invention is to yieldingly maintain the blank in predetermined positions on a horn during the forming of said blank into a metal body.

A still further object of the invention is to provide novel means actuated by a single handle for maintaining guide members in position to guide the blank on a horn.

A still further object of the invention is to provide novel means for engaging hook shaped ends of the blank with each other and form the blank to circular shape.

Further objects of the invention will herein-after appear in the description of the apparatus embodying the invention.

The embodiment of the invention comprises a pair of rails mounted below a hopper adjustable to support body blanks of various sizes in stack formation and the lowermost blank being separated from the stack of blanks by suction means comprising a suction cup adjustable to correspond with the adjustment of the hopper and normally positioned in spaced relation to the lowermost blank and actuated into engagement with the lowermost blank by the reciprocation of a carriage mounted below the suction cup. The suction cup is in communication with means to create a suction operative in synchronism with the reciprocation of a carriage to create a suction while the suction cup engages the lowermost blank and assumes its normal position with the lowermost blank attached thereto by suction. A feed bar carried by the carriage engages and strips the blank from the suction cup after the suction

cup assumes its normal position and positions said blank on the rails in alignment with pairs of cutters carried by a head adapted to be reciprocated toward and away from the rails to notch the corners of the blank on the rails to facilitate the securing of the opposite end portions of the blank together. The blank after it is notched is advanced on the rails by a pair of dogs mounted on a pair of feed bars carried by the carriage to a horn extending longitudinally from the rails and the blank is positioned by the pair of dogs on the horn relative to a shaping die carried by the head to bend the blank to U shape on the horn. After the blank is bent to U shape, it is advanced on the horn by a series of dogs carried by the pair of feed bars relative to guide members pivotally mounted to permit actuation of said members away from the horn for the purpose of inspection and removal of blanks which have jammed on the horn and said members are locked in guiding position by latches operated by a single handle. The blank is advanced by the series of dogs on the horn under the guiding members to bending tools reciprocatory laterally of the horn to bend laterally the free end portions of the blank on the horn preparatory to the forming of hooks at said portions, and then the blank is advanced by the series of dogs to tools reciprocatory vertically toward and away from said bent ends of the blank to form the hooks. After the hooks are formed, the blank is advanced by the series of dogs to a portion of the horn which is circular in cross section and to a pair of blades reciprocatory toward and away from the opposite sides of the horn to engage the hooked portions with each other and wrap the blank to circular shape about the horn. Then the circular shaped blank is advanced on the horn by the series of dogs to an anvil juxtaposed to the upper portion of the horn and a ram reciprocatory toward and away from the lower portion of the horn to clamp the engaged hooked portions together to form a securing seam of a completed body when the series of dogs move the formed metal body from the ram and off the horn.

In the drawings accompanying and forming a part of this application, Figure 1 is a side elevational view of apparatus embodying the invention.

Figure 2 is a plan view, on an enlarged scale, looking at the top of Figure 1, of an end portion of the apparatus arranged with the hopper, suction means for separating the lowermost blank from the stack of blanks in the hopper, the feed bar to advance the blank from the hopper and

suction means, the corner notching means, and the die to form the blank to U shape on the horn.

Figure 3 is a longitudinal section taken on the line 3—3 of Figure 2 looking in the direction of the arrows.

Figure 4 is a fragmentary perspective view showing adjustable mounting of the feeding bar for advancing the blank from the suction cup and the pair of feeding bars on the carriage.

Figure 5 is a sectional view, on an enlarged scale, taken on the line 5—5 of Figure 1 looking in the direction of the arrows and showing the structure of the suction creating means.

Figure 6 is a perspective view of the suction cup in its normal position and relative to means on the carriage for positioning the cup into engagement with the lowermost blank in the hopper.

Figure 7 is a sectional view of the suction cup showing the same actuated in engagement with the lowermost blank by the means on the carriage.

Figure 8 is a view showing the position assumed by the lowermost blank after it has been separated from the stack of blanks by the suction cup.

Figure 9 is a fragmentary view taken substantially on the line 9—9 of Figure 8 looking in the direction of the arrows and showing in dotted lines the stripping of the blank from the suction cup by the feeding bar.

Figure 10 is a sectional view, on an enlarged scale, taken on the line 10—10 of Figure 1 looking in the direction of the arrows to show the structure of the notching cutters.

Figure 11 is a sectional view, on an enlarged scale, taken on the line 11—11 of Figure 1 looking in the direction of the arrows to show the die for forming the blank to U shape.

Figure 12 is a fragmentary view similar to Figure 11 showing flexible members being actuated out of their normal position during the forming of the blank to U shape on the horn.

Figure 13 is a perspective view of the head carrying the cutters and shaping die shown in Figures 10 and 11.

Figure 14 is a side elevational view of the guide members for maintaining the U shaped blank on the horn and means for forming the hooks on the opposite end portions of the blank.

Figure 15 is a cross sectional view taken on the line 15—15 of Figure 14 looking in the direction of the arrows showing in dotted lines the guide members actuated to position away from the horn.

Figure 15a is a diagrammatic view of the blank shown in Figure 15.

Figure 16 is a perspective view in section showing the tools for bending laterally the opposite ends of the U shaped blank in their initial position.

Figure 17 is a view similar to Figure 16 showing the tools bending the opposite ends of the blank in a lateral direction.

Figure 17a is a diagrammatic view of the blank shown in Figure 17.

Figure 18 is a fragmentary view of the carriage showing a cam slot therein for the engagement of a roller carried by the bending tools shown in Figures 16 and 17 to actuate said tools laterally of the horn.

Figure 19 is a longitudinal section of the means for forming the hooks on the blank shown in Figure 14.

Figure 20 is a cross sectional view, on an enlarged scale, taken on the line 20—20 of Figure 14 looking in the direction of the arrows, showing the tools for forming the hooks on the blank.

Figure 21 is a perspective view of Figure 20 showing the tools actuated to position to form the hooks.

Figure 21a is a diagrammatic view of the blank shown in Figure 21.

Figure 22 is a perspective view of a feed bar of the pair of feed bars showing mounted thereon a dog of the pair of dogs and a dog of the series of dogs.

Figure 23 is a cross sectional view taken on the line 23—23 of Figure 1 looking in the direction of the arrows to show the pair of blades for engaging the hooks of the blank in their initial position.

Figure 24 is a view, on an enlarged scale, looking at the top of Figure 23 to show the blades in plan view.

Figure 25 is a fragmentary sectional view in perspective of the blades showing one of the blades positioning a hook juxtaposed to the hook engaged by the other blade.

Figure 26 is a perspective view of actuating means to impart reciprocation to the carriage.

Figure 27 is a cross sectional view, on an enlarged scale, taken on the line 27—27 of Figure 1 looking in the direction of the arrows to show the ram in its fully actuated position clamping the hooks of the blank together to form the securing seam of the metal body; and

Figure 28 is an elevational view of the ram in its initial position.

Like characters will designate like parts throughout the description of the apparatus disclosed in the accompanying drawings.

In carrying out the invention illustrated in the accompanying drawings the operative parts are mounted upon a suitable framework comprising a table T supported from a base B by standards S, and said operative parts are actuated from a drive shaft 29 rotatably mounted in bearing brackets 30 supported on one of the standards S. The shaft 29 is operatively connected to a suitable source of power, such as an electric motor, not shown, through a belt adapted to be engaged on a pulley 31 loosely mounted on the shaft 29 and adapted to be connected to said shaft by a clutch member 32 rotatable with and slidable on the shaft and actuated by a lever 33 pivotally mounted on the base B by a bifurcated bracket 34 and connected with the clutch member through a pin and slot connection 35 to permit rotation of the clutch member with the shaft 29, as shown in Figure 23.

Means to deliver a blank to the apparatus, notch the corners of the blank, form the blank to U shape, and engage the hooked portions of the blank with each other, are directly actuated from a shaft 36 rotatably mounted in bearings arranged in the standards S. The shaft 36 is driven from the drive shaft 29 through bevelled pinions 37 fixed on both shafts in meshing engagement with each other, as shown in Figure 27.

The bodies are formed from rectangular blanks b of sheet material supported in stack formation in a hopper comprising a pair of standards 38 fixedly mounted on the upper surface of the table T in spaced relation to each other and on opposite sides of the longitudinal axis of the table to constitute the side walls of the hopper with one standard nearer the axis than the other standard, and the inner face of both standards are recessed to form vertical edges for the engagement of an edge of the blanks at the opposite ends of the blanks, as at 39 in Figures 2 and 3. The blanks are supported in the hopper by shoulders 40 mounted on the standards 38 in the inner recessed 75

faces thereof to engage the opposite ends of the lowermost blank in the hopper, as clearly shown in Figures 5, 7 and 8. The hopper is adapted to support blanks of different widths to permit the forming of bodies of different lengths by arranging the sides of the hopper with a series of aligned pairs of vertical recesses 41 for the removable mounting of a plate 42 supported and retained in any pair of aligned recesses by screws 43, as shown in Figures 2 and 3. The adjustably mounted plate 42 releasably carries a bar 44 arranged with serrations adjacent the lower end to engage a side edge of the lower blanks, and maintain and support the blanks in stack formation in the hopper, as at 45 in Figures 3 and 9.

The lowermost blank in the hopper is separated from the stack of blanks by suction means comprising a suction cup 46 arranged on the upper edge of a block 47 having an air passage 48 extending therethrough and communicating with the cup and having an outlet through a side wall thereof. The suction cup carrying block 47 is adjustably mounted on a slide member 49 by a screw 50 threaded in the member 49 and engaging a slot 51 in the block 47 to permit adjustment of the suction cup corresponding to the adjustment of the plate 42. The member 49 is slidably mounted in a slideway formed by a U shaped bracket 52 having perforated bosses 53 extended from the leg portions thereof for the mounting of the bracket on a lower portion of one of the standards 38 by screws engaged in the perforations of the bosses and the standard, as shown in Figures 3 and 5. The member 49 is retained in the bracket 52 by a plate 54 secured to the ends of the leg portions of said bracket by screws and said plate being arranged with a flanged portion 55 at the upper edge thereof to extend into a recessed portion 56 in the member 49 and form an expansible chamber for a cylindrical spring 57 normally positioning the suction cup 46 in spaced relation to the lowermost blank in the hopper. The movement of the suction cup carrying block 47 in a downward direction under the force of the spring 57 is limited by a portion 58 extending laterally from the block 47 to abut the upper edges of the bracket 52 and plate 54, said lateral extension 58 having arranged therein the outlet of the air passage 48, as shown in Figure 7.

The suction used to separate the lowermost blank from the stack of blanks is created by a pump consisting of a cylinder 59 fixedly mounted on the base B and adapted to receive a piston 60 reciprocated in said cylinder by the rotation of the shaft 36 through a rod 61 pivotally connected at one end to the piston and the opposite end pivotally connected to a crank member 62 fixed to the end of the shaft extending from the standard S. The lower portion of the pump cylinder is connected in communication with the air passage 48 in the suction cup carrying block 47 through a rigid pipe line 63 supported by the frame work B, S, T, and connected to the air passage 48 through a flexible hose 64 engaged at the opposite ends on the pipe 63 and a nozzle 65 fixed in the air passage outlet in the block extension 58 to permit reciprocation of the block 47. In the operation of the pump the inward stroke of the piston will force the air from the cylinder through a valve, as indicated at 66, connected to the bottom of the cylinder and adapted to be actuated to open position by the pressure in the cylinder created by the inward stroke of the piston, thereby preventing air pressure entering the pipe line 63, and the

outward stroke of the piston closing the valve 66 and creating a suction in the pipe line 63. To control the suction at the suction cup a shut off valve is arranged in the pipe line 63 actuated by a handle 67.

The suction cup carrying block 47 is actuated against the force of the spring 57 to position the suction cup in engagement with the lowermost blank in the hopper by the reciprocation of a carriage or slide 68 slidably mounted in a channel slideway 69 arranged in the top of table T along the longitudinal axis thereof, as shown in Figure 5. The carriage is arranged with a cam 70 fixedly mounted in the upper face thereof and having an oblique cam face to co-operate with an oblique cam face on the slidable member 49 and move said member in a direction toward the hopper against the force of the spring 57. The carriage is reciprocated and the cam is moved relative to the member 49 in synchronism with the actuation of the suction pump by the rotation of the drive shaft through a shaft 71 rotatably mounted parallelly of the drive shaft in bearings 72 carried by the table T and the standard S, Figures 1 and 27, the shaft 71 being driven from shaft 29 through gears 73 fixedly mounted on the ends of said shafts. The shaft 71 reciprocates the carriage 68 through a crank disk 74 fixedly mounted on said shaft and having a crank pin 75 engaging a block 76 slidable in a vertical recess 77 in a cross head 78 having a horizontal slot 79 engaging the shaft 71 and an arm 80 connected to the carriage by screws, as at 81 in Figure 23.

The actuation of the carriage 68 and the piston 60 of the suction pump is in synchronism so that a suction is being created during the engagement of the suction cup 46 with the lowermost blank and said suction is maintained during the actuation of the cam 70 out of engagement with the slidable member 49 and the lowering of said member by the spring 57 to separate the lowermost blank from the stack of blanks.

The movement of the suction cup having the lowermost blank attached thereto by suction from its fully actuated position to its normal position will flex the attached blank as the opposite ends of said blank will be engaged by the shoulders 40 of the hopper, as shown in Figure 8. This flexing of the lowermost blank will ensure the separation of said blank from its adjacent blank.

The blank separated from the stack of blanks in the hopper is stripped from the suction cup by a feed bar 82 adjustably mounted at one end on a supporting block 83 fixedly mounted on the upper face of the carriage 68 with the opposite end of the bar bifurcated and a plate 84 spanning the bifurcation to form a recess in the underface of the feed bar to permit reciprocation of the bar past the suction cup 46, as shown in Figure 3. The forward end of the plate 84 is bevelled and extended beyond the legs of the bifurcated end of the feed bar to engage and prevent the blank attached to the suction cup from assuming a flat position while the blank is moved from the suction cup and along the shoulders 40, said shoulders being rounded, as shown in Figure 8, to facilitate the moving of the blanks from the hopper.

After the blank is stripped from the suction cup and removed from the hopper it is positioned by the feeding bar 82 on a pair of supporting rails 85 mounted on a die plate 86 secured to a supporting block 87 mounted on the face of the

- table T, as shown in Figure 10. The blank assumes its normal flat condition when it is positioned on the rails and is maintained on the rails in such condition by a pair of guide rails 88 of angular shape with one angle portion having a lateral flange for the engagement of screws to attach and support the guide rails on the adjustable plate 42 of the hopper, as at 89 in Figure 2, with the other angle portion extending in parallel spaced relation to the blank supporting rails 85, as shown in Figure 3. The rails 85 support the blank in flat condition relative to means for notching the corners of the blank to facilitate the forming of the side securing seam of the metal body and the attachment of the heads to the formed body, comprising two pairs of cutters 90, each pair of cutters being integral with a plate 91 releasably mounted on a flange of a pair of flanges 92 integral with and extended from the underface of a cross head 93 supported and connected by lateral extensions 94 to a pair of slides 95 slidably mounted in standards 96 fixedly supported on the face of the table T at the opposite sides thereof. The cutters may be readily removed from the flanges 92 by screws 97 to be substituted for cutters that are spaced different distances corresponding to the width of the blanks which are being operated on to form bodies of predetermined length and will correspond to the adjustment of the plate 42 of the hopper, as indicated in dotted lines at 88 in Figures 3 and 13. The cutters are reciprocated toward and away from the rails 85 and die plate 86 from the shaft 36 through an eccentric disk 99 fixedly mounted on the shaft 36 and adapted to be engaged by a strap 100 having an internally screw threaded boss 101 for the adjustable engagement of a screw threaded link 102 screw threaded in a screw threaded socket member 103 engaged between and pivotally connected to a pair of cross members 104 connected at the opposite ends to the lower end portions of the slides 95, whereby the cutting stroke of the cutters may be varied by the turning of the link 102 by an abutment plate 105 connected to the link and adapted to be clamped to the boss 101 and socket member 103 by a screw 106 engaged in an intermediate portion of the link 102. The die plate 86 is arranged with four openings 107 co-operating with the cutters 90 to notch the corners of the blank, as at n, and the supporting block 87 and table T are arranged with corresponding openings to permit the scrap metal to drop from the apparatus, as at 107 in Figure 10.
- 55 The blank is advanced from the notching cutters 90 and the supporting rails 85 to means for bending the notched blank to U shape in cross section by a pair of dogs in the form of a lever 108 having a blank engaging head arranged at 60 the forward end thereof with a projecting portion to engage over the upper surface of the blank, as at 109 in Figure 22, and pivotally mounted at the rear of the head in a bifurcated portion of a bracket 110 fixedly mounted on the side of a feed bar of a pair of feed bars 111 supported at one end in recesses in the side portions of the block 83 of the carriage 68 and releasably retained in said recesses by clamping plates 112 releasably secured to the block 83, as shown in Figures 3 and 4. The bifurcated portions of the dog supporting brackets 110 extend above the feed bars 111 and the heads of the dog levers 108 are yieldingly urged in an upward direction away from the feed bars by a helical spring 113 engaged between the dog lever heads

and the brackets 110, to engage the rearward edge of the blank on the rails 85 after the notching of the blank with the projecting portions 109 of the dog heads extending over the upper surface of said blank to retain the blank in engagement with the dog heads. The blank engaged by the dogs 108 is maintained in flat condition during the travel from the notching means to the bending means by the guide rails 88 and a rail 114 supported adjacent one end thereof by a cross member 115 mounted at the opposite ends on the supporting block 87, with the rails 88 also being supported by the cross member on opposite sides of the rail 114, as clearly shown in Figure 11.

15 The blank is positioned by the dogs 108 in superposed relation to a male die member in the form of a horn 116 having an outer contour of an inverted U and mounted against lateral displacement in a supporting block 117 supported on the top of the table T to straddle the channel slide-way 69 and the carriage 68, as shown in Figure 11. The blank being supported by the horn is bent about the same to inverted U shape by a shaping or female die comprising a block 118 20 removably carried by the head 93 and having a U shaped recess 119 in the lower face thereof to engage and bend the blank about the horn during the downward movement of the head, as shown in Figure 12, whereby a blank is formed 25 to U shape at the same time another blank which has been stripped from the suction cup 46 is notched by the cutters 90. The recess 119 is arranged with a slotted portion 120 extending vertically into the block 118 to accommodate the 30 guide rail 114 in the fully actuated position of the forming die block 118. To prevent the opposite end portions of the U shaped blank from springing away from the horn while the die block 118 is reciprocated to its initial position, a pair of 35 plates 121 of resilient material, such as spring steel, are fixed at one end portion to vertical extensions 122 of the horn supporting block 117 with the opposite end portions terminating adjacent the opposite sides of the horn, as shown 40 in Figures 2, 11 and 12. To permit the bending of the blank on the horn without interference with the resilient plates 121, said plates are moved to a position away from the horn by a pair of rods 123 slidably mounted in the head 93 45 on opposite sides of the shaping die 118 and retained in the head by collars 124 fixed on an end portion of the rods to abut the upper face of the head with the lower ends of the rods yieldingly urged away from the head by a cylindrical spring 50 125 engaged on each rod and compressed between the under face of the head and collars 124 fixed on the rods adjacent the lower ends thereof, whereby the initial downward movement of the head 93 will engage the rods with the resilient plates 121 and flex said plates against wear resisting inserts 127 in the supporting block 117, the continued movement of the head 93 moving the rods 123 toward the head against the force of the springs 125, as shown in Figure 55 12. The forward end of the forming die block 118 is cut away, as at 128 in Figure 3, to accommodate the dogs 108 during the downward movement of the die block.

70 The horn 116 is mounted on the supporting block 117 to extend in vertical alignment with the longitudinal axis of the table T, and the hopper 38 is mounted on one side of the longitudinal axis of said table T, as shown in Fig. 7, so that the bending of the blank on the horn 75

will position one end of the blank to extend below the opposite end of the blank, as shown in Figures 16 and 17.

After the blank is formed to U shape it is engaged by the first pair of dogs of a series of pairs of dogs 129 pivotally mounted in recesses 130 in the outer side wall of each of the feed bars 111 with an end portion of each dog yieldingly urged by a spring 131 (Figure 22) to extend laterally from the outer sides of the feed bars to engage the rearward edge of the U shaped blank b on the horn, the feed bars being slidably supported in recesses in the opposite sides of the horn 116, as at 132. The reciprocation of the feed bars 111 in a forward direction will move the blank engaged by the first pair of dogs 129 to a pair of guide members 133, 134 having laterally extending angular arms 135 fixed thereto with the free ends of the arms arranged with bosses 136 rotatably engaged on studs 137 fixedly mounted in ears 138 fixed to spaced plates 139 fixedly supported on a table T so that the guide members may be adjusted to positions to enclose the upper surface of the horn which is engaged by the U shaped blanks b and to permit an inspection of the horn and the removal of any blank that may have jammed on the horn. The inner faces of the guide members 133, 134 are arranged with arcuate shape longitudinal channels corresponding to one half of the upper surface of the horn, as at 140, to maintain the blank in U shape on the horn while the opposite end portions of the blank extending below the horn are formed to hooked shape.

The blank is intermittently fed along the horn to various devices for forming the opposite end portions of the blank to hooked shape by the reciprocation of the feed bars 111 and the engagement of preceding pairs of dogs 129 with the rear edge of the U shaped blank to position said blank to a succeeding device for forming the hooks. During the retrograde movement of the feed bars the dogs 129 are positioned within the recesses 130 against the force of the springs 131 by the engagement thereof with the blanks on the horn and to prevent movement of the blanks from their actuated positions by the dogs during the retrograde movement of the feed bars, pins 141 are slidably mounted in perforations in the guide members extending at an angle to the vertical axis of the members in a downward direction from the exterior walls to the arcuate channels 140 with end portions of the pins having a flat longitudinal face 141' yieldingly urged to project from the surface of said channels by springs 142 fixed at one end to the guide members by screws 143 engaged in the outer face of the guide members 133, 134 with the opposite ends engaged in the ends of the pins extending from the outer face of the guide members. The pins are spaced equidistantly apart to engage the flat faces 141' with the rear edges of the blanks predeterminedly positioned on the horn by the dogs 129, as shown in Figures 14 and 19. The moving of the blanks by the dogs 129 to their predetermined positions will force the pins 141 into the guide members 133, 134 against the force of the springs 142 until the blanks reach their predetermined positions when the flat faces 141' of the pins are positioned by the springs 142 into the channels 140 to engage the rear edges of the blanks.

The guide members 133, 134 are releasably retained in their closed position to maintain the blanks on the horn by a pair of latch members 144 having one end of hooked shape and the op-

posite ends arranged with eccentric openings engaged on eccentrics, as shown at 145, fixedly supported on a shaft 146 rotatably mounted in bosses 147 extending vertically from the guide member 134. The latch members are actuated in a longitudinal direction, as shown in dotted lines in Figure 20, by a handle 148 fixed to the shaft 146 intermediate the ends thereof, into and out of engagement with a shaft 149 supported at the opposite ends in bosses 150 extending vertically from the guide member 133. The actuation of the latch members out of engagement with the shaft 149 will permit the moving of the guide members 133, 134 on their pivots 137 to open position, as shown in dotted lines in Figure 15.

The second pair of dogs 129 on the feed bars 111 will engage the blank positioned by the first pair of dogs 129 relative to the guide members 133, 134 and position said blank relative to means to bend laterally the opposite ends of the blank extending below the horn 116 preparatory to the forming of said ends to hooked shape comprising a pair of tools 151, 152 (Figures 14 to 19, inclusive), removably mounted on opposite sides of a flange 153 extending vertically from the face of a plate 154 fixed to a slide 155 slidably supported on the top of the table T in a slideway formed by the opposing sides of the plates 139, as shown at 156 in Figures 14 and 19. The bending tool 151 is normally positioned on one side of a die member 157 mounted in a recess in the side of the horn 116 juxtaposed to the inner surface of the longer end portion of the blank and tool 152 is normally positioned on one side of a die member 158 carried juxtaposed exteriorly to the shorter end of the U shaped blank by the connecting portion of a U shaped supporting member 159 having the leg portions thereof integral with the plates 139. Subsequent to the positioning of a blank by the second pair of dogs 129 relative to the die members 157, 158, the slide 155 is actuated transversely of the horn 116 by the reciprocation of the carriage 68 through a cam roller 160 carried by the slide 155 and engaging an angle portion of a cam slot 161 in the carriage 68 having a straight portion at the rear end and the angle portion at the front end so that the retrograde movement of the carriage will flange the opposite end portions of a blank positioned relative to the die members 157, 158.

After the opposite end portions of the blank are bent laterally, as shown at f in Figure 17, the blank is moved away from the die members 157, 158 by the third pair of dogs 129 to a position where no operation is performed on the blank and from this position the blank is advanced by the fourth pair of dogs 129 relative to a die member 162 carried by the horn 116 in a recess in a side of the horn juxtaposed to the inner surface of the longer end portion of the blank, as shown at 163 in Figures 20 and 21, and a die member 164 mounted on the support 159 on the side of the horn opposite to the recessed side 163 and in a higher plane than the die member 162 to correspond to the difference in length of the opposite end portions of the blank and engage the outer surface of the shorter end portion of the blank above the flange thereof. The blank is positioned by the fourth pair of dogs 129 with the flanged end portions f of the blank extending below the die members 162 and 164, which have an angle shaped projection 165 on their faces adjacent the end portions of the blank to form the flanged end portions of the blank to hooked shape by bending tools 166 and 167, releasably mounted on the

opposite sides of a flange 168 extending vertically from the upper face of a plate 169 adjustably mounted on a slide 170 slidable between a plate 139 at one end and members of pairs of spaced 5 members 171 fixed on the table T at the opposite end of the slide. The tool 167 extends a greater distance from the flange 168 than the tool 166 to co-operate with the die members 164, and the tools 166 and 167 are yieldingly urged away from the 10 die members 162, 164 and the slide normally maintained on the table T by helical springs 172 mounted in recesses 173 in the vertical flange 168 with the upper ends abutting the bottom of the horn 116. Subsequent to the positioning of the 15 blank relative to the die members 162, 164 and the bending tools 166, 167, said bending tools are actuated toward said die members to engage the end portions of the lateral end portions of the blank and bend the lateral end portions to hooked 20 shape, as shown at h in Figure 21, over the angle shaped projections 165 of the die members 162, 164 by the retrograde movement of the carriage 68 through a cam 174 fixed to the upper face of the carriage and having a progressing angular 25 cam face to engage a corresponding face of a central recess 175 in the underface of the slide 170 and move the slide 170 with the bending tools 166, 167 against the force of the springs 172 toward the die members 162, 164.

30 After the hooks h have been formed by the tools 166, 167, the blank b is advanced by the fifth pair of dogs 129 to a circular portion of the horn 116, as shown at the right hand side of Figure 14, where the hooks h are engaged with each other 35 and the blank formed to circular shape while the blank is maintained on the horn by the guide members 133, 134, by a pair of blades 176, 177 carried by blocks 178 slidable in slideways 179 on the table T formed by the members 171 and said 40 blades being adapted to be adjustably retained on the blocks by screws 180 threaded in the blocks and engaging slots 181 in the blades, and adjusted toward and away from the horn by set-screws 182 adjustably mounted in vertical flanges 183 at the 45 outer sides of the blocks 178. The inner end of the blade 176 is arranged with a bevelled edge inclining from the lower face of the said blade to the upper face at an acute angle to the plane of the blade, as shown at 184 in Figure 25, and the 50 inner end of the blade 177 is bevelled at an obtuse angle to the plane of said blade, as at 185 in Figure 25. The blade 176 is adapted to be actuated toward the horn 116 to engage the bevelled edge 184 with the hook h of the shorter end of the 55 blank b on the horn and position said hook in an elliptical recess 186 in the lower portion of the horn (Figure 25) when the bevelled edge 185 of the blade 177 engages the longer end portion of the blank and positions the hook of said end portion below the hook of the shorter end portion of the blank engaged in recess 186, so that the hook of the shorter end portion of the blank will engage the hook of the longer end portion of the blank engaged by the blade 177 under the tension of the material of the blank when retrograde movement is imparted to the blade 176 and the bevelled edge 184 is disengaged from the hook of the shorter end portion of the blank, as shown in dotted lines in Figure 25. The blades 176, 177 60 are actuated from the shaft 36 through a pair of levers 187, 188 pivotally mounted in bifurcated hangers 189 suspended from the table T with one end of the levers bifurcated and extended through an opening 190 in the table T to engage a pin 191 fixed between the legs of a bifurcated portion 65

70

75

192 of the slide blocks 178 carrying the blades 176, 177, respectively. Cam rollers 193, 194 are carried by the opposite end portions of the levers 187, 188, respectively, and yieldingly urged by a spring 195 to engage cam disks 196, 197, respectively, fixedly mounted on the shaft 36 in spaced relation to each other to rotate in a direction indicated by the arrow in Figure 23 and arranged to actuate the blade 177 in sequence to the actuation of the blade 176 in the manner hereinbefore described. 10

After the hooks h are engaged with each other the blank is advanced on the circular portion of the horn 116 by the sixth pair of dogs 129 to means to clamp the engaged hooks to each other 15 to form a securing seam of the metal body comprising an anvil 198 adjustably mounted on an arm 199 extended upwardly from the standard S in an arcuate direction over the table T, and retained in adjusted position by set screws 200 screw 201 threaded in a flange 201 of the arm whereby the anvil engages an intermediate portion of the blank. The hooks h of the blank are engaged by a ram or bumper having a head 202 and a shank 203 slidably mounted in a slideway 204 arranged 20 in a plate 205 supported by the table T with the slideway extending through the table T, as shown in Figure 27, to adapt the foot of the shank to be engaged by a cam roller 206 carried by the crank disk 74 and secured to the hub of said disk by arcuate plates 207 secured to the hub on opposite sides of the roller, as shown in Figure 26. The head 202 is arranged with a presser member 208 slidable in a recess in the head and having an angle face yieldingly positioned to extend above 30 the head by a spring 209. In the lower position of the ram the presser member 208 is positioned in spaced relation to and on one side of the axis of the horn 116 under the downward angular force of a spring 210 carried by a set screw 211 40 adjustably mounted in an angle portion 212 of the plate 205 with the free end of the spring engaging a protuberance extending at an acute angle from the ram shank 203, as at 213. The upward movement of the ram toward the horn will position a 45 lateral projection 214 at the foot of the shank 203 in engagement with a cam face 215 fixed to the lower portion of the slideway 204 and a cam shoe 216 fixed to a side of the head 202 in engagement with a cam face in the form of a plate 217 50 adjustably mounted on a vertical extension 218 of the plate 205 and adapted to be adjusted toward or away from the travel of the ram by set screws 219 mounted in a vertical flange 220 of the vertical extension 218 whereby lateral movement is 55 imparted to the ram against the force of the spring 219 to position the presser member 208 into engagement with and force the engaged hooks h of the blank b into a rectangular recess in an anvil plate 221 mounted in the lower portion of the 60 horn, and the continued upward movement of the ram being in a vertical direction forces the presser member 208 into the head 202 and engages a presser plate 222 mounted on the ram head with the hooks of the blank to clamp and form the 65 hooks into a securing seam, as shown in Figure 27.

After the forming of the seam, the metal body b is completed and is removed from the horn by the seventh and eighth pairs of dogs 129 into a suitable depository or relative to an apparatus for 70 securing heads on the opposite ends of the spool body, as shown in Figure 1.

The feed bars 82 and 111 are adjusted to feed blanks of different widths by set screws 223, 224 adjustably mounted on a vertical extension 75

225 of the carriage block 83 to engage the rearward ends of the feed bars 82 and 111, respectively, as shown in Figures 2, 3 and 4.

The carriage 68 and supporting channel 69 are lubricated by a lubricant, such as mineral oil, carried by a receptacle 226 mounted on the carriage 68, as shown in Figure 3. To prevent an accumulation of dirt about the lubricating receptacle and the feeding bar support 83, there is provided a U shaped shield 227 mounted on the table T, as shown in Figures 1 to 3, inclusive.

Having thus described my invention, I claim:

1. In apparatus for forming metal bodies, a pair of rails fixedly mounted to support a blank in a substantially flat condition, means to notch the corners of a blank supported on the rails comprising a pair of slides reciprocally mounted at the outer sides of the rails, a cross member mounted on and connecting the slides above the rails, cutters releasably mounted on the cross member in alignment with the corner portions of the blank, and actuating means connected to the slides to impart reciprocating movement to the cutters in a direction perpendicularly toward to and away from the blank to cut notches in the corner portions of the blank, and reciprocating means mounted to engage the center portions of the blanks and move the blanks along the rails to and away from the notching means.

2. In apparatus for forming metal bodies, a reciprocating carriage, a hopper mounted above the carriage and arranged to support body blanks in stack formation, suction means reciprocally mounted between the horizontal planes of the carriage and hopper normally positioned in spaced relation with the lower blank in the hopper and actuated by the reciprocation of the carriage into engagement with said lower blank and separate said blank from the stack of blanks in the hopper by assuming its normal position, and means carried by the carriage to engage the blank engaged by the suction means and move said blank from the suction means by the reciprocation of the carriage.

3. In apparatus for forming metal bodies, a reciprocating carriage, a hopper mounted above the carriage and arranged to support body blanks in stack formation, suction means reciprocally mounted between the horizontal planes of the hopper and carriage and yieldingly urged to position in spaced relation with the lower blank in the hopper, means arranged on the carriage to engage and move the suction means into engagement with the lower blank in the hopper by the reciprocation of the carriage, the suction means separating the lower blank from the stack of blanks in the hopper on assuming its normal position, and means carried by the carriage to engage and strip the blank from the suction means by the reciprocation of the carriage.

4. In apparatus for forming metal bodies, a reciprocating carriage, a hopper mounted in superposed relation to the carriage and arranged to support body blanks in stack formation, a member slidably mounted between the horizontal planes of the carriage and the hopper to have movement toward and away from the hopper and having an air passage therein opening to the upper face thereof, means to normally position the slidable member in spaced relation to the lower blank in the hopper, means to create a suction connected to the air passage in the slid- able member, means arranged on the carriage to engage and move the slidable member to position the upper face thereof into engagement with the

lower blank in the hopper, and means to actuate the carriage and suction creating means in synchronism to create a suction when the upper face of the slidable member is engaged with the lower blank and reciprocate the carriage to permit the slidable member to assume its normal position and separate the lower blank from the stack of blanks while the suction is maintained.

5. In apparatus to form metal bodies as claimed in claim 4, a feed bar of U shape carried by the carriage to engage and move the blank from the slidable member by the reciprocation of the carriage, and a plate fixed to and spanning the bifurcation of the U shaped feed bar with an end portion projecting from the forward end of the bar to engage the upper face of the blank.

6. In apparatus to form metal bodies, a reciprocating carriage, a hopper mounted above the carriage and arranged to support body blanks in stack formation, a slideway mounted between the carriage and the hopper and having a lateral projection intermediate the ends thereof, a member slidably mounted in the slideway and having a recessed portion to accommodate the projection of the slideway, a suction cup carried by the slidable member in the face thereof, a spring engaged between a wall of the recess in the slidable member and the projection of the slideway to normally position the suction cup in spaced relation with the lowermost blank in the hopper, suction creating means connected to the suction cup, a cam fixed on the carriage to engage the slidable member and move said member against the force of the spring to position the suction cup into engagement with the lowermost blank in the hopper, and means to actuate the carriage and the suction creating means in synchronism to create a suction when the cam engages the slidable member and position the cam out of engagement with the slidable member to permit said member to assume its normal position under the force of the spring and separate the lowermost blank from the stack of blanks while the suction is maintained.

7. In apparatus to form metal bodies, a reciprocating carriage, a hopper mounted above the carriage having a wall adjustable toward and away from the opposite wall of the hopper to support in stack formation body blanks of different widths, a member slidably mounted between the horizontal planes of the carriage and the hopper to have movement toward and away from the hopper and yieldingly urged away from the hopper, a suction cup adjustably mounted on the slidable member to have adjustment on said member corresponding to the adjustment of the wall of the hopper, means to create a suction connected in communication with the suction cup, means arranged on the carriage to engage and move the slidable member toward the hopper and position the suction cup into engagement with the lowermost blank in the hopper, and means to actuate the carriage and suction creating means in synchronism to create a suction when the suction cup is engaged with the lowermost blank and reciprocate the carriage to permit the slidable member to assume its normal position and separate the lowermost blank from the stack of blanks while the suction is maintained.

8. In apparatus to form metal bodies as claimed in claim 7, a feed bar carried by the carriage and adapted to engage and strip the blank from the suction cup by the reciprocation of the carriage in positioning the movable member engaging

means out of engagement with the movable member.

9. In apparatus to form metal bodies as claimed in claim 7, a feed bar carried by the carriage to engage and strip the blank from the suction cup in the normal position of the slideable member, and guide rails supported on the exterior of the adjustable wall of the hopper and extended therefrom in a horizontal plane to engage the upper face of the blank while it is stripped from the suction cup by the feed bar.

10. In apparatus to form metal bodies as claimed in claim 7, a feed bar adjustably mounted on the carriage to have adjustment corresponding to the adjustment of the wall of the hopper to properly engage and strip the blank from the suction cup in the normal position of the slideable member.

11. In apparatus to form metal bodies, means to support a blank in flat condition, cutter means reciprocatory toward and away from the blank on the supporting means to notch the corner portions of said blank, a horn extending longitudinally from the means to support the blank in flat condition, means reciprocatory in a vertical direction toward and away from the upper portion of the horn to engage a blank in flat condition and form said blank to U-shape on the horn, and means to successively move the blanks along the blank supporting means and the horn to be operated on by the means to notch and form the blank to U shape.

12. In apparatus to form metal bodies, a horn, means to bend a body blank about the horn to U shape in cross section comprising a head slidably mounted to extend transversely above the horn and have movement toward and away from the horn, and a bending die carried by the head to engage the blank in flat condition and bend said blank about the horn to U shape, resilient members fixed at one end with the free ends terminating adjacent to the opposite sides of the lower portion of the horn, and members carried by the head and yieldingly urged in a direction away from the head to engage and flex the resilient members in a direction away from the horn during the movement of the head and die toward the horn to permit the bending of the blank about the horn by the die and the movement of the head and die from the horn positioning the members carried by the head out of engagement with the resilient members and permitting the resilient members to assume their normal position and maintain the blank in U shape on the horn.

13. In apparatus to form metal bodies, means to support a body blank in flat condition, a horn having a U shaped contour and extended longitudinally from the means to support the body blank, a head slidably mounted to extend transversely above the means to support the body blank in flat condition and the horn and have movement toward and away from said means and horn, cutters carried by a portion of the head above the means to support the body blank in flat condition to notch the corners of the blank during the movement of the head toward said supporting means, and a bending die carried by the portion of the head above the horn to bend the blank to U shape about the horn during the movement of the head toward said horn.

14. In apparatus to form metal bodies as claimed in claim 13, a pair of feed bars slideable in opposite side portions of the horn, a dog mounted on each bar and yieldingly positioned

to extend above the bars to engage and move the blank along the blank supporting means from the cutters to the bending die, a series of dogs mounted on each feed bar in equidistantly spaced relation to each other and yieldingly positioned to extend laterally from the bars to engage the opposite leg portions of the U shaped blank and intermittently advance the blank along the horn, and means to reciprocate the feed bars.

15. In apparatus to form metal bodies as claimed in claim 13, a pair of guide members, each member having an arcuate face portion corresponding to one half of the upper contour of the horn and pivotally mounted on opposite sides of the horn to have movement toward and away from the adjacent side of the horn, latches carried by one of said members adapted to be actuated into and out of locking engagement with the other member when the members are positioned juxtaposed to the horn to maintain and guide the U shaped blank on the horn.

16. In apparatus to form metal bodies as claimed in claim 13, a pair of guide members, each member having an arcuate face portion corresponding to one half of the upper contour of the horn and pivotally mounted to have movement toward and away from the horn, and a series of pins slidably mounted in each member and yieldingly urged to extend from the arcuate faces to abut the rear edges of the U shaped blanks on the horn when the members are positioned juxtaposed to the horn to maintain the blanks in adjusted positions on the horn.

17. In apparatus for forming metal bodies, a table, a carriage reciprocally mounted on the table, a horn supported by the table above the carriage, a series of dogs slidably mounted on the horn and operatively connected to the carriage, a hopper mounted on the table and arranged to support blanks for the metal bodies in stack formation, suction means reciprocally mounted on the table below the hopper and normally positioned in spaced relation with the lower blank in the hopper and adapted to be actuated by the carriage into engagement with said lower blank to separate said blank from the stack of blanks, cutters reciprocatory toward and away from the table adapted to notch the corners of the blanks, means fixed on the carriage to engage the separated blank engaged by the suction means and move said blank from the suction means to position relative to the corner notching dies, a die reciprocatory toward and away from the horn to bend a notched blank over the upper face of the horn with the opposite ends of the blank extending below the horn, means actuated transversely of the horn by the reciprocation of the carriage to flange laterally the ends of the blank extending below the horn, means actuated toward and away from the lower face of the horn by the reciprocation of the carriage to form the flanged ends of the blank to hook shape, a pair of blades mounted on the table on opposite sides of the horn adapted to be actuated in sequence to each other to engage the hooked ends of the blank with each other, and a ram reciprocatory toward and away from the lower face of the horn to engage and clamp the engaged hooked ends of the blank together and form a securing seam of a metal body.

18. Apparatus for forming metal bodies as claimed in claim 17, wherein the horn is mounted out of alignment with the center of the hopper whereby the bending die will bend the blank

over the horn with one end of the blank extending below the opposite end of the blank.

19. In apparatus for forming metal bodies, a horn having a U-shape portion and a circular portion, means to bend a flat blank to U shape in cross section on the U-shaped portion of the horn with the opposite marginal portions of said blank extending parallelly to each other, means operative to form the opposite marginal portions of the U shaped blank to hook shape, means to maintain the blank in U shape during and after the forming of the marginal portions to hook shape, a pair of blades slidably mounted on opposite sides of the blank positioned on the circular portion of the horn and actuated toward and away from the blank with one blade adapted to be actuated in sequence to the other blade to catch the hooked portions of the blank with each other and form the blank to circular shape in cross section during the movement of the blades toward each other, means to clamp the engaged hook portions together and form a securing seam of a metal body, and means to advance the blank to the successive operating means.

20. In apparatus for forming metal bodies, a horn having a U shaped portion and a circular portion, means to bend a flat blank to U shape in cross section on the U shaped portion of the horn with the opposite marginal portions of said blank extending parallelly to each other, means operative to form the opposite marginal portions of the U shaped blank to hook shape, means to maintain the blank in U shape during and after the forming of the marginal portions to hook shape, a pair of blades slidably and adjustably mounted to have adjustment toward and away from the opposite sides of the blank positioned on the circular portion of the horn and actuated toward and away from the blank, the movement of the blades toward each other catching the hooked marginal portions of the blank with each other and forming the blank to circular shape in cross section, means to clamp the engaged hook portions together and form a securing seam of a metal body, and means to advance the blank to the successive operating means.

JOHN A. JOHNSON.

25
